UNITED STATES PATENT OFFICE.

JOSEPH FOLK, OF LA PORTE, INDIANA, ASSIGNOR TO U. S. SLICING MACHINE COMPANY, OF LA PORTE, INDIANA, A CORPORATION OF INDIANA.

SLICING MACHINE.

Application filed January 29, 1926. Serial No. 84,591.

This invention relates to machines for slicing meat or other commodities and its object is to provide a device for receiving scraps which fall from the slicing knife and 5 to so relate said receiving device to the other parts of the machine that it will be easily accessible for removal and will not interfere with surrounding objects. The invention is in the nature of an improvement on the 10 device shown in Patent No. 1,314,560, granted September 2, 1919, to J. C. Woodington.

The invention is exemplified in the combination and arrangement of parts shown in the accompanying drawing and described in 15 the following specification, and it is more particularly pointed out in the appended claims.

In the drawing—

Fig. 1 is a perspective view showing a portion 20 of a slicing machine having one embodiment of the present invention applied thereto;

Fig. 2 is a fragmentary vertical section substantially on the cutting plane of the 25 slicing knife and shows the scrap pan in longitudinal section;

Fig. 3 is a transverse section of the scrap pan and a portion of the slicing knife.

In the drawing, the numeral 10 designates 30 the frame of the slicing machine having a table 11 mounted for reciprocation thereon and having a rotary slicing knife 12 for severing slices carried by the table 11. The knife 12 is journaled on a pedestal 13 arranged at one side of the path of the reciprocating table 11. It will be noted that the 35 knife 12 projects below the table 11 and small particles of meat or other material being sliced are frequently carried down and discharged from the knife at the lower portion thereof. These particles lodge between the edge of the base 10 and the support 13 at a point not easily accessible. Scrap receiving trays or pans have been previously 40 provided, but such trays are in the form of a slide arranged to be drawn outwardly at the rear of the slicing machine, that is, at the side of the knife opposite the cutting portion and opposite the slice receiving plate.

It is customary in slicing machines to provide 45 a shield, at the front side of the knife supporting pedestal, and where the scrap pan is inserted from the rear care must be taken in inserting the scrap pan to move it forwardly to an exact position so that no

space is left for material to enter between the front edge of the scrap pan and the rear face of the shield. A greater inconvenience of this form of construction, however, is due to the fact that the pan must be withdrawn 60 at the rear of the slicing machine when it is to be emptied. This is of great inconvenience especially when the slicing machine is placed upon a counter having a glass front. On such a counter, the rear of the machine 65 must be arranged adjacent the glass front so that the scrap pan is made inaccessible and can only be removed by shifting the position of the slicing machine. The position of the scrap pan with the handle at the rear also 70 makes it invisible to the operator so that it is liable to be overlooked, and not regularly emptied.

In the present invention, the shield shown 75 at 14 in the drawing has its inner edge, adjacent the knife 12, substantially straight and does not project inwardly to cover the space 15 at the front of and below the knife 12. The scrap pan 16 is slidably mounted in the space between the pedestal 13 and the base 80 10 but is arranged to slide forwardly over the slice receiving table 17 instead of rearwardly. The forward end of the pan 16 carries a plate 18 which covers the space 15 when the pan is slid to its innermost position. The plate 18 has a forwardly projecting portion 19, the upper edge of which extends to a position adjacent the lower edge 85 of the knife 12 as shown in Fig. 2. The rear end of the pan 16 is provided with a notch 90 or slot 20 which permits the pan to be moved in and out of position although the sides of the pan project above the lower edge of the knife 12. A liner or guide 21 receives the pan 16 and is provided with an overhanging ledge 22 for guiding particles into the pan 16. A guard plate 23 is hinged to the inner edge of the shield 14 and is normally swung inwardly against the side of the knife 12. The lower end of the guard plate 23 is 95 provided with an extension 24 which closes against the edge of the plate 18 and projects beyond the edge of the knife 12 for that portion of the knife below the table 11. The guard plate 23 may be swung outwardly 100 to permit cleaning of the knife and the scrap pan 16 is withdrawn by sliding it forwardly from its recess. It will be seen that in this forward movement the tray moves over the slice receiving plate 17 so that if any scraps 105 110

fall from the pan they will be intercepted by the plate 17 and will not fall into inaccessible positions or upon the floor.

I claim:—

- 5 1. The combination with a slicing machine having a rotary slicing knife and a reciprocating table for moving material toward the cutting side of said knife, of a scrap pan disposed beneath said knife, said 10 pan being removable at the side of said knife adjacent the cutting side thereof.
2. The combination with a slicing machine having a rotary slicing knife and a reciprocating table for presenting material to said 15 knife to be sliced, of a scrap pan slidable into and out of position beneath said knife, said pan being removable from said position by forward movement thereof toward the cutting side of said knife, and means on said 20 pan to limit rearward movement thereof to prevent removal of said pan rearwardly.
3. The combination with a circular slicing knife, of a scrap pan disposed beneath said knife, said pan having the sides thereof overlapping the sides of said knife and having a notch in the rear end thereof to permit said pan to be slid forwardly out of operating position beneath said knife.
4. In a slicing machine, a rotary circular 30 slicing knife, a reciprocating table for presenting material to said knife, a plate for receiving slices, and a scrap pan disposed beneath said knife, said scrap pan being slid from beneath said knife by movement 35 thereof over said slice receiving plate.
5. In combination, a slicing machine having a supporting frame, a pedestal spaced from said frame, a knife mounted on said pedestal, a scrap pan disposed beneath said 40 knife between said frame and pedestal, and a shield at the front side of said pedestal,

said scrap pan having a plate at the forward end thereof arranged to register with said shield when said scrap pan is in position beneath said knife. 45

6. A slicing machine comprising a frame, a pedestal spaced from said frame, a rotary circular knife journaled on said pedestal, a reciprocating table mounted on said frame for presenting material to said knife to be sliced, and a scrap pan disposed between said frame and pedestal, beneath said knife, said scrap pan being provided with a front plate having the upper edge thereof disposed adjacent the edge of said knife. 50 55

7. A slicing machine comprising a frame, a pedestal spaced from said frame, a circular slicing knife journaled on said pedestal, a shield secured to the front side of said pedestal, a scrap pan disposed between said pedestal and frame, beneath said knife, said scrap pan having a front plate, the lower portion of which registers with said shield while the upper portion is inclined outwardly, and a guard plate hinged to said shield 60 and disposed adjacent the outer edge of the outwardly inclined portion of the front plate of said scrap pan. 65

8. A slicing machine comprising a frame, a pedestal spaced from said frame; a knife 70 journaled on said pedestal, a scrap pan disposed between said frame and pedestal, beneath said knife, a reciprocating table mounted on said frame, and a slice receiving plate disposed beneath said table at the forward edge of said knife, said scrap pan being removable by movement thereof forwardly above said slice receiving plate. 75

In testimony whereof I have signed my name to this specification on this 26th day of January, A. D. 1926. 80

JOSEPH FOLK.
